MICROPHONE ARRANGEMENT

Erwin Gerlach, Berlin, Germany, assignor to Tele-funken Gesellschaft für Drahtlose Telegraphie m. b. H., Berlin, Germany, a corporation of Germany

Application February 2, 1938, Serial No. 188,249
In Germany February 19, 1937

8 Claims. (Cl. 179—1)

The invention relates to improved microphone apparatus and particularly to microphones for electro-acoustic transmissions wherein there is required the setting up of larger amplifiers, control apparatus, distribution stations, etc., at a centrally located place. In such an arrangement, the microphone is set up at a distance from the central operating station and requires the use of a cable having a multiplicity of wires 5 for connecting the line between the microphone and the main control station. The length of such a cable is often several hundred meters, the operating voltages required by a microphone having an amplifier stage mounted thereon can be applied to the microphone across the cable, but if cables having only two wires are to be used for the transmission, a preliminary amplifier is required in the direct proximity of the microphone. This preliminary amplifier supplies the microphone with the proper voltages. A condenser-microphone with tube, for example, requires a tube heater voltage, plate voltage and grid voltage. 10

It has been found undesirable to mount the preliminary amplifier directly on the microphone. 15 Therefore, it will be more appropriate to place the preliminary amplifier at a distance of about ten to twenty meters from the microphone because in this arrangement the said amplifier can be set up outside the field of vision which will be 20 of great importance in case of sound film recordings, opera transmissions, transmissions of speeches, etc.

In accordance with this invention, the microphone with its amplifier stage mounted thereon 25 is built into a simple unit within a container together with a cable which is subdivided in two portions, one portion having a length of ten to twenty meters and is connected between the microphone and the preliminary amplifier. The 30 construction is as follows: the preliminary amplifier is arranged in the center of a cable drum so that when winding or unwinding the cable, the amplifier will likewise be turned. This affords the advantage that the end of the cable 35 for the preliminary amplifier remains fixedly connected with the amplifier. Thus, during the operation, the winding or unwinding can be carried out without the necessity of connecting to slip rings and the like, which lines have direct 40 voltage and are very sensitive to disturbances at the places of contact. Even when during operation or testing there is no reason to vary the length of the line, it would not be proper to use slip rings as they cause the possibility of crackling 45 noises.

In accordance with a further feature of this invention, when slip rings are employed to permit spool 3 to rotate independently of spool 2, they are placed in the low impedance circuit of the actual distance line containing two wires. 5 The danger of slip ring noises is in this case extremely small. Obviously, it is also possible to connect the double wire distance line to fixed terminals instead of slip rings. At the winding and unwinding, this connection must then be 10 opened.

In many cases, it may be desirable to mount a cable drum on the apparatus having double wire distance cable connected thereto so that there will always be connected a part of the 15 double wire cable directly with the preliminary amplifier so that in cases where the place at which the preliminary amplifier is to be set up is also suitable for setting up other amplifiers, the connection with the amplifier can always be 20 immediately established.

The protective casing for the apparatus surrounds both cable drums, the slip rings and the preliminary amplifier. The cables emerge through two openings. An especially provided 25 space (not shown) within the protective casing serves for accommodating the microphone so that when the latter is packed up it need not be separated from the cable.

The figure shows an example embodying the 30 idea of the invention. A casing or a drum 1 preferably formed of sheet metal has two cable spools 2 and 3 rotatably mounted therein. The cable spool 2 serves for winding on the cable 5 leading to the microphone 4. An operating crank 15 is 35 fastened to shaft 16 for rotation of spools 2 and 3. The spool 3 has wound thereon the double wire line 6 through which the useful frequencies are passed to the main amplifier or frequency input source. In order to eliminate improper contacts to which preliminary amplifiers are extremely sensitive, the preliminary amplifier 7 indicated by the dash lines inside the cable spool 2 is fixedly mounted within said spool 2, so that it will turn when the cable for the microphone 45 is being wound on. The terminals to which the microphone cable is connected are designated by 8, and the terminals from which the connections lead to the main amplifier, namely the output terminals of the amplifier 7, are designated by 9. 50

As can be seen from the arrangement shown, the microphone cable is fixedly connected to the microphone, as well as to the preliminary amplifier, so that difficulties due to improper contacts such as are encountered when using slip rings 55

- in the portion of the cable, will not be possible. In order that the impulses furnished by the amplifier 7 can be applied to the main amplifier, slip rings 10 and 11 must be provided at the likewise rotatable cable spool 3 and which cooperate with the brushes 12 and 13 to complete the circuit. The brushes are connected to the output terminals 9 of the amplifier 7. Since the slip rings are placed in the low impedance circuit, the 5 possibility of appearance of crackling noises and other disturbances due to the contacts are reduced to a minimum. The casing or drum 1 is suitably so dimensioned that the entire cable, as well as the microphone 4, can be accommodated there-in. In this case, the opening 14 must be large enough to permit insertion of the microphone 4. This opening will then preferably be closed up by means of a sliding cover. In this way, a single unit that can be easily carried is obtained 10 and which fulfills all requirements as regards simple handling and compactness. This is of importance in case of microphones used for reporting, for talking film recording, transmission of speeches, etc.
- 20 25 If a still simpler construction is desired, the possibility exists of accommodating only the cable spool 2 including the preliminary amplifier 7 within the cable drum. Such construction may be considered, for instance, where the cable drum is to be placed in direct vicinity of the central amplifier station.
- 30 35 40 45 50 55

What is claimed is:

1. A microphone arrangement comprising a casing, a cable and spool located within said casing, said spool having a hollow portion adjacent the winding space for said cable, and an amplifier, which is electrically connected to said microphone by said cable, disposed within said hollow portion.
2. A microphone arrangement having a wound-on line cable comprising a casing for enclosing a spool for said cable, an amplifier mounted to rotate within said spool, and means including said cable electrically connecting said microphone and amplifier directly together.
3. A microphone arrangement comprising a casing for enclosing a microphone, a microphone cable divided into a plurality of portions, and a rotatable spool for each divided portion of said cable, an amplifier mounted to rotate within one of said spools, and means including one portion of said cable electrically connecting said microphone and amplifier directly together.
4. A microphone arrangement comprising a

casing for enclosing a microphone, a microphone cable divided into a plurality of portions, and a rotatable spool for each divided portion of said cable, an amplifier mounted adjacent one of said spools, and means including that portion of the cable which is wound upon the spool adjacent said amplifier forming a direct-connection between said microphone and said amplifier. 5

5. A microphone arrangement comprising a casing for enclosing a microphone, a microphone cable divided into two portions, two separate winding spools for said cable portions, an amplifier arranged to rotate with one of said spools, one portion of said cable being wound on one of said spools and connected directly to said microphone and said amplifier, the other portion of said cable being wound upon the other spool and serving as a connection from said amplifier to a utilization point. 15

6. A microphone arrangement comprising a 20 casing for enclosing a microphone, a microphone cable divided into two portions, two separate winding spools for said cable, an amplifier arranged to rotate with one of said spools, one portion of said cable being wound on one of said 25 spools and connected directly to said microphone and said amplifier, the other portion of said cable being wound upon said other spool, said last-mentioned spool having slip rings located thereon, and means for connecting said amplifier 30 through said slip rings to said other portion of said cable.

7. A microphone arrangement comprising a casing for enclosing a microphone, a microphone cable divided into two portions, two separate 35 winding spools for said cable, one of said spools having a large central aperture, an amplifier located within said central aperture and arranged to rotate with said one spool, one portion of said cable being wound on said spool having the large 40 central aperture and being connected directly to said amplifier and said microphone, the other portion of said cable being wound upon said other spool and serving as a connection between said amplifier and a utilization point. 45

8. A microphone arrangement comprising a casing having an aperture sufficient to permit the insertion of said microphone, a cable and spool located within said casing, said spool having a hollow portion adjacent the winding space for said cable, and an amplifier disposed within said hollow portion which is electrically connected to said microphone by said cable. 50
